BAG FILLING MACHINE

Howland F. Briggs, Buffalo, N. Y., assignor to
 Bagpak, Inc., New York, N. Y., a corporation
 of Delaware

Application May 2, 1935, Serial No. 19,396

26 Claims. (CL 226—56)

My invention relates to a machine for filling and closing bags, particularly large open mouth gusseted multi-ply bags made of rigid unyielding material, such as kraft paper, adapted to be filled with one hundred pounds more or less of pulverulent or granular materials. My invention of course may be utilized to fill and close bags formed of other materials, or paper bags having a single ply, or bags adapted to contain but a small charge of material, but it is to be kept in mind that my invention is peculiarly designed with a view to overcoming difficulties and problems encountered in the filling and closing of large multi-ply paper bags.

My present invention is an improvement upon the structure described and claimed in the co-pending application of Robert N. Cundall and Lincoln A. Cundall, Serial #688,816, filed September 9, 1933, with particular reference to the filling machine embodied in the invention. My invention comprises improvements in the construction and arrangement of the machine as set forth herein, these improvements having been found to increase materially the operation, speed and efficiency of the machine while reducing the bulk thereof and otherwise contributing to its commercial success.

One of the objects of my invention is to devise means for holding the mouths of bags as they are being filled in a turret filling machine, the bag holding means being so constructed that the bag mouths are automatically drawn shut after the charge is placed in the bag, without danger of the bag mouth being torn or marred by the holding clamps.

Another object of my invention is to devise improved automatic means for actuating the bag holding clamps in order that the bags may be firmly and positively gripped before any material is dumped thereinto.

Another object of my invention is to devise improved means whereby the bag is moved around the central post of the turret during the time that it is being filled and until it is ejected from the turret.

Another object of my invention is to devise improved means for removing the bag from the turret and conveying it to closing and sealing mechanism.

Other and further objects and advantages of my invention will be apparent from the following description taken in connection with the accompanying drawings wherein like numerals refer to like parts throughout:

Referring to the drawings:

Fig. 1 is a plan view of my improved bag filling and closing machine;

Fig. 2 is a side elevation of the machine;

Fig. 3 is a view partly in elevation and partly in section, of the filling turret on an enlarged 5 scale showing features of my invention, and having some parts removed for clarity;

Fig. 4 is a sectional view of the turret taken along line 4—4 of Fig. 3;

Fig. 5 is a sectional view of the turret taken 10 along line 5—5 of Fig. 3;

Fig. 6 is a view in elevation of one of the filling spouts and its associated bag gripper taken along line 6—6 of Fig. 4 and showing the clamps in open position;

Fig. 7 is a view similar to Fig. 6 but showing the clamps in closed position;

Fig. 8 is a schematic representation of a bag in several positions on the turret, showing the closing of the bag mouth as the bag is jogged 20 after being filled; and

Fig. 9 is a detailed view of gripper actuating mechanism.

Referring to Figs. 1 and 2, my invention comprises a rotary turret A upon which large open 25 mouth bags, particularly multi-ply paper bags, are adapted to be held and wherein they are filled with pulverulent or granular materials from weighing mechanism B mounted above the turret. After the bags are filled they are released 30 from the turret and positioned upon a conveying device C wherein they are closed by closing mechanism D and the closed mouths are sealed by a tape applied by mechanism E. The tape and stitches between bags are severed by means of 35 a shears F and the bags are ejected from the machine. The details of the weighing mechanism B, the closing mechanism D, the tape applying mechanism E and the shears F are not within my present invention; the details thereof preferably 40 correspond to similar mechanism described and illustrated in the aforementioned copending application. Any specific similar mechanism may be employed, it being sufficient for the purpose of my invention that the bags are filled with the 45 correct charge of material and are closed and ejected from the machine.

The turret and the closely associated parts comprising my present invention will now be described:

The turret comprises a central, fixed post 20 mounted upon a standard 21 and supported at its upper extremity by a framework 22. Surrounding post 20 is a revolving sleeve 23 supported by thrust bearings 24, and to the lower extremity 55

of which is fixed a gear 25. Gear 25 and the attached sleeve 23 are rotated by means of a worm 26 mounted upon a shaft 27 and driven by means of bevel gears 28 and a power shaft 29. Shaft 5 29 is rotated by suitable means (not shown).

The turret comprises a suitable number of hoppers, numbered 30 to 39 inclusive in Fig. 1, for the purpose of relating various positions of the bag in its travel around the turret. A greater 10 or lesser number of hoppers may be employed if desired. The weighing mechanism B comprises a plurality of scales, in this instance two, but of which a greater or lesser number may be employed. Means are provided to operate the scales 15 alternately, one being discharged while the other is weighing a predetermined charge. The scales are tripped by means of mechanism comprising a feeler 45 and associated parts. The weighing scales alternately discharge into a chute 46, the 20 open end of which is located above the upper ends of the hoppers. The shape of the open end of the chute 46 is preferably substantially segmental in order that its sides will be within the limits of the segmentally shaped hoppers during the time 25 that the material is being discharged. The feeler comprises a swinging arm mounted upon a vertical rod 41, the upper end of which carries an arm bearing a spool 48 adapted to be interposed between one arm of a bell crank 49 and a vertical 30 scale-tripping rod 50. The bell crank 49 is rocked by each one of a series of adjustable lugs 51 associated with the turrets, and when the spool 48 is interposed between the bell crank and the rod 50 one of the scales will be discharged. The spool 35 is interposed only when the feeler 45 senses the presence of a bag. The feeler and scale-tripping mechanism are more fully described and illustrated in the aforesaid copending application.

The operator, standing at the position indicated 40 by the hoppers 30 and 31, inserts a bag which is clamped by mechanism, to be described, before the hopper reaches position 33. As the lug 51 engages bell crank 49 one of the weighing scales will be tripped and discharged at the position of 45 hopper 33 (Fig. 1). The chute is so proportioned as to allow the passage of the entire charge before the trailing edge of hopper 33 passes beyond the rearward edge of the chute. It is to be appreciated that no discharge will occur if the feeler 45 50 senses the absence of a bag and swings inward to the position shown in Fig. 1.

The bottom of each hopper is extended into an oval-shaped filling spout 55 adapted to be inserted within the mouth of an open-mouth bag. 55 A band 56 circling the spout 55 acts as an upper limit against which the operator positions the upper edge of the bag. The front of each spout is provided with a temporary holding device, preferably two devices being provided. The holding device comprises a bracket 57 (Fig. 6) having a depending arm to which is pivoted a horizontal arm 58. On the inner end of arm 58 there is mounted a roller 59 bearing against the surface of the spout 55. A spring 60 attached to the outer 60 end of arm 58 and to bracket 57 tends to hold arm 58 in substantially horizontal position, the length of the arm being such that roller 59 cannot pass below a horizontal line through the pivot of arm 58. However, when a bag mouth is 65 forced upward the roller will allow insertion of the bag material between itself and the wall of the spout, while the spring 60 will cause the roller to clamp against the bag material with sufficient force to hold the empty bag. The grip of 70 rollers 59 is so slight that the operator is enabled 75

to slide the bag vertically or from side to side in order accurately to position it with respect to the spout and with respect to the bag clamps which are to be described.

A collar 65 is fixed to the rotating sleeve 23 and 5 mounted upon the collar are a series of hinge blocks 66, there being one block for each hopper. A clamp-holding arm 67 is pivoted to the block 66 and is resiliently supported in substantially horizontal position by a spring 68 extending from the arm to a disc 69 fixed to the sleeve 23. A pair of spaced collars 70 and 71 are fixed to sleeve 23 below collar 65 and retain a loosely mounted collar 72 in correct position. Collar 72 carries a cam 73 engaged by rollers 74 mounted upon 10 brackets 75 fixed to the lower surface of arm 67. A pair of bars 76 and 77 is fixed to the collar 72 and extends to a portion of the frame to conveyor C, serving to prevent rotation of cam 73 15 about the post 20.

The bag is placed upon the filling spouts by the operator at position 30 and/or 31. It will be filled at position 33, in which position roller 74 engages the relieved portion of cam 73 and the arm 67 begins to tip in order that the bottom of the bag 20 may rest upon a lower support while the total length of the bag shortens due to the bulging of its sides. The lowering of arm 67 gradually continues until in position 38 it remains substantially 25 in its lowermost position. Immediately upon 30 passing that position the arm is sharply raised by a sharp projection of cam 73.

Spaced rods 78 and 79 are mounted upon the flange of collar 72 and support a shoe 80 which converges toward the cam 73, forming a converging passageway in which roller 74 may be positively 35 engaged and held at its innermost position, and correspondingly the arm 67 will be held at its lowermost position during the time that the hopper passes through position 38 until shortly before 40 it reaches position 39. The hinge block 66 is formed with an abutment preventing arm 67 from passing above a horizontal position as it is lifted by the force of spring 68.

Arm 67 supports bag grippers which positively 45 hold the bag during the time that it is being filled and until it is deposited in the conveyor C, the rollers 59 merely being temporary holders which are incapable of supporting the bag as it is being filled. The outer end of the arm is provided with 50 a flange 86 to which is bolted a bracket 87 extending laterally of the arm and having a pair of spaced upwardly extending portions 88 and 89. Supported by portion 88 is a fixed gripper G and supported by a portion 89 is a pivoted gripper G'. 55 Grippers G and G' are substantially duplicates in construction, the sole difference between the two lying in the mounting therefor, gripper G being mounted upon a support 90 bolted to portion 88 and prevented from rotation with respect thereto, 60 while gripper G' is mounted upon a rod 91 extending from portion 89 and is capable of rotation with respect thereto. As seen in Fig. 8, gripper G always remains in a vertical position while gripper G' swings outward from the vertical. 65

Support 90 extends forward slightly beyond the leading edge of spout 55 and is provided with a depending arm 92 in the lower end of which is mounted a knurled disc clamp 93 slightly to the rear of the center line of the spout 55 and slightly 70 below the ring 56. An operating arm 95 is pivoted to the forward end of support 90 and is provided with an extension at right angles thereto, forming in effect a bell crank. A movable jaw 96 carrying a spring-pressed knurled disc clamp 97 75

is pivoted to the arm 92. An intermediate link 98 is pivoted to operating arm 95 and to the jaw 96, the extension of arm 95 and the link 98 forming a toggle adapted to open and close the movable jaw 96. A spring 99 extends between pins mounted upon support 90 and arm 95 and tends to retain the arm in the position illustrated in Fig. 6, with the toggle broken and the jaws open in order that the edges of a bag may be slipped between the clamps 93 and 97. Arm 95 carries a roller 100 which is engaged by suitable mechanism to open and close the jaws at the proper time. In Fig. 6 the arm is in its uppermost position about to be engaged by mechanism to lower the arm and close the jaws. In Fig. 7 the arm is slightly above its lowermost position having been forced downward against the tension of spring 99. As the clamp 97 engages the material of the bag its spring will be compressed and the jaw 96 will be swung to such an extent that the toggle link 98 may travel past dead center, thereby locking the jaw in closed position. Each of the jaws will be successively closed, and at the proper instant mechanism will engage and raise the roller 100 causing link 98 to again pass over dead center whereupon spring 99 will snap arm 95 upward and open the jaws practically instantaneously.

Gripper G' is a duplicate of gripper G except that it is mounted upon the rod 91 extending from portion 89. A sleeve 105 provided with a depending lever 106 is slipped over the rod and against 89. A second sleeve 107 is bolted to the first sleeve by a bolt 108, and carries the operating mechanism of the jaws and the clamps. A link 109 is pivoted to lever 106 and to one arm of a bell crank 110 pivoting about a post 111 mounted upon bracket 87. The opposite arm of bell crank 110 is fixed to a link 112 extending above and parallel to arm 67. A bitt 115 extends from the hinge block 66 and link 112 slidably passes therethrough. Lock nuts 116 define the limit to which link 112 may pass through the bitt and a compressed spring 117 held on the link by other adjustable lock nuts 118 normally retains the lock nuts 116 against the bitt.

It can be seen that as arm 67 pivots downwardly, link 112, forming in effect one side of a parallelogram, will cause bell crank 110 to pivot and force link 109 toward gripper G' until a predetermined force prevents such motion and causes further compression of spring 117. As arm 67 is raised the link 112 will rock bell crank 110 back to the original position.

Since link 109 is fixed to the lever 106 gripper G' will rock outwardly about rod 91 the farther that arm 67, and correspondingly the bag, is lowered. This occurs during the time that the bag passes through positions 34, 35, 36 and 37. As the bag reaches position 37 the contents thereof should have been completely settled and the bag will have bulged and shortened and due to the lowering of arm 67 its mouth will have been dropped below the spout 55. Due to the rocking of gripper G' the bag mouth will be drawn closed into a taut straight line, the tension upon the bag mouth being determined by the compression of spring 117.

In order positively to cause the bag mouth to be located in an exact horizontal line, properly aligned with the operating mechanisms adjacent conveyor C, the shoe 80 forces roller 74 against cam 73 as the bag passes through position 38. It can be seen that were it not for spring 117 such positive lowering of the arm might easily result

in ripping or chewing of the bag mouth. Due to the spring the arm may be lowered without continued rocking of gripper G' beyond a point allowed by the width of the bag. This is of extreme importance inasmuch as the operator may not always draw the mouth of the bag tautly against the sides of the spout. If the bag mouth is loosely drawn gripper G' will have to rock to a greater extent than if the bag mouth were tautly drawn.

In order positively to close and open the grippers at the proper instants, there are provided cams which contact with the rollers 100 on the arms 95. A cam 125, suitably positioned upon the framework of conveyor C, forces arms 15 95 upward as soon as the bag reaches the conveyor. The cam is so positioned that gripper G will be opened as soon as the leading edge of the filled bag enters the grip of the conveyor, and the trailing gripper G' will be opened as soon 20 as the entire bag has entered the conveyor and its mouth gripped and held in closed position to be presented to the closing and sealing mechanism. Cam 125 merely starts the arm upward, and as soon as the toggle is broken, spring 99 25 will cause the jaws to snap open, in order that the bag will be held by the grippers until the absolutely correct moment. This cam is similar to the corresponding cam described and claimed in the aforementioned copending application.

In order to close the grippers, I have devised a novel mechanism which comprises a movable shoe so operated as to close the jaws in a much shorter period of time than would be possible with a fixed cam. I have found this to be desirable since a fixed cam tended to swing the movable gripper, which swinging movement was naturally prevented by the fixed gripper, both grippers being clamped to the bag mouth surrounding the filling spout. Quite often this resulted in 40 a bag being torn or marred.

My novel mechanism comprises cams 126 and 127 mounted upon a shaft 128, driven by a chain 129 from a parallel shaft 130 driven by a gear 131 meshing with a gear 132 at the end of driven shaft 27 (Fig. 5). A yoke 140, slidably guided by shaft 128, is positioned between cams 126, 127 and carries rollers 141, bearing upon cam 126, and 142 (Fig. 2) bearing upon cam 127. A vertical rod 143 fixed to yoke 140 is positively 50 raised and lowered by the cams 126 and 127. Rod 143 passes through a bitt in a lever 144, pivoted to the frame 22. An adjustable lock-nut on rod 143 supports the lever 144 in substantially horizontal position and an adjustable spring 145 55 surrounding the rod above the lever 144 forces it to follow the reciprocation of rod 143, spring 145 allowing continued reciprocation of the rod in case the lever should be held against movement. A shoe 146 is fixed to the free end of 60 lever 144. Cam 127 is provided with two sharp elevations spaced about 120° apart. Cam 126 is provided with two depressions so related to the elevations on cam 127 as to allow downward movement of shoe 146 when the elevations on 65 cam 127 engage roller 142.

An inspection of Fig. 4 shows that grippers G and G' are spaced about twice as far apart as the grippers G and G' of adjacent spouts. Cam 126 raises the shoe 146 to the position indicated in Fig. 6 and cam 127 sharply lowers the shoe at the instant that one of the rollers 100 comes beneath it. The reciprocations of the shoe will occur twice in rapid succession with a longer following dwell in order that each gripper may be 75

closed by positive reciprocating mechanism. Shoe 146 is turned upwardly at its front edge to provide a cam-shaped shoe, assisting in the downward movement of the arms 95. The spring 145 5 allows the shoe to remain stationary in case a jaw should be jammed, and allows continued movement of rod 143 even after the jaws have been completely closed.

As the bags progress around the turret they 10 are jogged in order to settle the contents into the bags. This jogging action is accomplished by means of an arcuate platform 150 positioned beneath the filling spouts from stations 33 to 37 inclusive. Mounted in the platform are a series 15 of radially extending rollers 151 adapted to engage and support the bottom of the bags as they are filled and lowered onto the platform by the arms 67. Platform 150 is supported by a frame 152 pivoted at 154 and 155 to allow pivoting of 20 the platform, and supported adjacent its central portion by roller 156 bearing upon a rotating cam 157 having two or more sharp depressions. Platform 150 is hinged to a short intermediate section 158 extending to the belt conveyor 159 in 25 conveyor C. Cam 157 is rotated by a vertical shaft 160, the lower end of which is supported in a frame 161 carrying cushioning elements 162 against which the frame 152 is dropped by the action of the cam. Shaft 160 extends upward to 30 a gear box 164 mounted upon frame 22 and is driven by a motor 165 (Figs. 1 and 2).

As the bags are filled and lowered onto the conveyor 150, their contents will be jogged by the rapidly shaken roller conveyor 150. The rollers 35 151 provide frictionless support for the bottom of the bag in order that undue strains will not be placed upon it. However, I have found that considerable strain is placed upon the bag in spite of the rollers, resulting in the bag being distorted, its edges torn or marred, or its being disengaged from the gripping jaws, so that the mouth of the bag will not be maintained in a horizontal line or at the correct height. Inasmuch as the mouth of the bag is gripped in the 45 conveyor C and presented to the closing mechanism in the same alignment that it is received by the conveyor, it is important that it should not slip the clamps. In order to prevent this I have developed bag pushing means, specifically 50 illustrated in Figs. 3 and 5.

Spaced collars 170 and 171 are attached to the rotating sleeve 23, and support a loosely mounted collar 172 prevented from rotating by bars 173 and 174 extending to the conveyor frame, similar 55 to bars 76 and 77. Below collar 171 is a disc 175 welded, or otherwise affixed, to sleeve 23 for rotation therewith. A series of radially extending bars 176 are mounted upon disc 175, being one for each spout. Suitable braces 177 may be provided to prevent bars 176 from being distorted. A bell-crank 178 is pivoted at 179 to bar 176, one end of which carries a roller 180. An arm 181 is also pivoted on the pivot 179 and is connected to the free arm of bell-crank 178 by an 60 adjustable pin and slot connection. A lug 182 upon arm 181, engages with an adjustable screw 183 fixed in bar 176 to prevent undue inward movement of roller 180 under the force of a spring 184 extending from arm 181 to an adjacent bar 70 176.

During the time that the hoppers are in positions 39, 30, 31 and 32, the spring 184 holds lug 182 against the screw 183, and bag-pushing plates 185, fixed to the ends of arms 181, will be held to 75 the rear of the empty bags and out of the way of

the bags as they are being placed on the turret. With the pusher-plates 185 held in retracted position, the trailing edge of an empty bag will be substantially contacting therewith, but as the bag fills and the sides bulge, the edges of the bag will be drawn toward each other and the pusher-plates would be practically useless were it not for the following mechanism: A number of adjustable rods 190 are extended radially from the flange of collar 192 and support a circular cam 191 having a relatively sharp forward edge at 192 against which the rollers 180 engage as the bag is being filled. The roller will ride onto the fixed portion of cam 191 before the bag leaves the filling station, so that as the bag fills the pusher-plate will be caused positively to follow the retarding edge of the bag. During the time that the bag is being jogged and the turret passes through stations 34, 35, 36, 37, and part of 38, the pusher-plate will be held against the rear edge of the filled bag in order to maintain it in substantial vertical alignment in spite of the retarding friction of its bottom on the conveyor 150. The end of cam 191 has a slightly relieved portion 193 which allows the pusher-plate to recede slightly in order that its tip will not be caused to travel faster than the conveyor C. As the bag is completely gripped in the conveyor and the grippers released, roller 180 drops from the cam 191 and the pusher-plate is retracted to clear the bag in the conveyor and to allow room for a succeeding empty bag.

As explained in the aforesaid copending application, when the mouth of the bag is released from the turret and gripped in the conveyor C, the gussets, and/or the plies of a multi-ply bag would tend to slip due to the translation from rotary movement to tangential, straight line movement. To correct this, the invention in the aforesaid application comprises means whereby the leading edge of the bag was received between the bag mouth gripping chains after a third of the bag had passed a line drawn normal to the conveyor C through the center of the turret. The same principle is embodied in the present structure, but in this instance the bag gripping chains 200 and 201 are passed about drive wheels 202, 203 respectively, mounted in alignment with a normal drawn through the center of the turret, but spaced at such a distance apart that the bag mouth cannot be gripped therebetween. Chain 200 is forced inwardly by a guide rail 204 and chain 201 is forced inwardly by spring pressed guide rails 205, the form of the guide rails being such that the chains are brought into gripping relationship at substantially one-third of a bag mouth from the normal drawn through the center of the turret. The advantage of this construction is that the chains do not diverge as abruptly as they would if passed around closely positioned drive wheels, and the bag mouth is gradually compressed into a single plane. I have found that with this construction there is no slippage of the plies relative to one another.

In Fig. 4, an empty spout is shown at positions 39 and 30. In positions 31 to 38 inclusive, the mouth of a bag is indicated upon each of the spouts. In positions 31 and 32, the bag is held in position by the temporary grippers 59. In positions 33 and 34, the bag mouth is gripped by the grippers G and G' and is still in fully open position before the arm 67 descends. In position 35 the bag mouth is being closed, and is closed in positions 36, 37 and 38. In position 38, the bag mouth is substantially in alignment with the center line of the conveyor C.

It is to be noted that the closing of the bag mouth is rapidly accomplished due to a relatively sharp depression 207 on cam 73 extending between positions 34 and 35. This allows rapid lowering of the bag immediately after the charge is dumped thereinto in order that the bag may expand without undue strain being placed upon the material lengthwise of the bag. In position 35 the bag mouth is still slightly open but will be closed very shortly due to a continued sloping portion 208 of cam 73, and as the bag reaches position 36 its mouth will be closed sufficiently to prevent the escape of dust as it is being jogged. In position 37 the roller 74 does not quite touch the edge of cam 73 which is now concentric with the post 20. This enables the entire bag to be jogged vertically, the weight of the bag tending to force roller 74 against cam 73 while the tension of spring 68 tends to lift the roller away from the cam. In position 38 the shoe 80 has positively forced roller 74 against cam 73, there being little or no jogging effect at this position, and the bag mouth being thereby drawn as tautly closed as permitted by the strength of spring 117 in order that it may be properly presented to the gripping chains 200 and 201.

Fig. 6 discloses a useful and novel feature of the bag gripping jaws. The spring pressed clamp 97 is projected to a point above and slightly to one side of the fixed clamp 93 when the jaws are open. The operator, in placing a bag, may shift it vertically and laterally in spite of the slight grip of the rollers 59, and in so doing he places the edges of the bag between the clamps 93 and 97 where they will be held by slight frictional pressure depending upon the strength of spring 209 and the position of the lock-nuts on the plunger carrying the clamp. In this manner the edges of the bag are aligned with the grippers and need not be held manually until shoe 146 closes the grippers. This is of particular advantage in handling large, multi-ply gusseted paper bags, of which the gussets are easily disarranged, and if disarranged prevent proper closing or may break the closing mechanism.

A further advantage of the clamps 93 and 97, particularly with respect to the movable gripper G', is in the fact that they are rotatably mounted in the jaws 92 and 96. The diagrammatic Fig. 8 shows that as grippers G' are canted, the mouths of the bags would be disarranged or the outer surface would be marred were it not for the fact that the clamps are free to rotate within the jaws.

A further feature of my improved machine is in the provision of a conical hood 210 covering the space within the rotating hoppers, being fixed thereto and provided with a sleeve of resilient material 211 bearing against the central shaft 20. The hood and sleeve provide means to prevent dust from dropping into the bearings and moving parts of the mechanism. With gritty materials, the abrasion by sharp particles soon ruins contacting faces and destroys any accuracy of the machine, and with some materials such as sugar, the dust combines with oil in the bearings to form a hard cake preventing rotation of the machine.

In Fig. 4 may be seen inner false walls 215 at each side of the spouts 55 forming vents for the escape of trapped air from the bags as they are being filled. These vents are preferably as illustrated and described in the copending application of Howland F. Briggs, Serial No. 757,761, filed December 17, 1934, and the filling spouts are

preferably otherwise formed in accordance with the invention therein disclosed and claimed.

The bags are conveyed by the belt 159 with their mouths gripped in closed position by the belts 201 and 202, and successively closed by means of closing mechanism D comprising a sewing head 220, preferably of the double-thread chain stitch type as illustrated in the copending application of Howland F. Briggs and Robert N. Cundall, Serial No. 689,400, filed September 14, 1933, and 10 preferably applying a reinforcing cord 221 in the manner described and claimed in the patent to Robert N. Cundall, No. 1,963,652. After being sewed, the bag mouths are presented to the tape applying mechanism E, preferably as described 15 and claimed in the copending application of Robert N. Cundall and Lincoln A. Cundall, No. 666,114, filed April 14, 1933, and thereafter the tape and thread is clipped by suitable clipping mechanism F. The mechanism D, E and F are 20 driven by suitable gears and shafts or other means (not shown) from the shaft 29 in order that all may operate continuously and synchronously with the turret. Suitable safety devices (not shown) are provided automatically to stop the entire machine in case of a jam at any position. 25

It will, of course, be appreciated that other mechanism than the specific aforementioned structure, may be substituted in place of the parts D, E and F, but the above are suitable and 30 preferred structures.

The preferred embodiment of my invention is described and illustrated, but it will, of course, be apparent to those skilled in the art that modifications in arrangement and detail may be made 35 without departing from the spirit of the invention, and it is my intention to claim as my invention all such substitutions, modifications and alterations as will come within the terms of the following claims. 40

I claim:

1. A bag filling machine comprising a filling spout, a pair of bag gripping devices, each comprising means to receive and grip the corner of a bag mouth, located one at each side of said spout, 45 and a pivoted arm carrying said gripping devices whereby the bag may be raised and lowered with respect to said spout, one of said gripping devices being rigidly mounted upon said arm and the other of said gripping devices being pivotally 50 mounted upon said arm whereby the distance between the effective gripping points of said gripping devices may be varied to open and close the bag mouth gripped thereby in order that said spout may be inserted partially into the bag during the filling thereof and that the bag mouth may be drawn closed thereafter. 55

2. A bag filling machine comprising a filling spout, a pair of bag gripping devices, each comprising means to receive and grip the corner of a bag mouth, located one at each side of said spout, 60 a pivoted arm carrying said gripping devices whereby the bag may be raised and lowered with respect to said spout, one of said gripping devices being rigidly mounted upon said arm and the other of said gripping devices being pivotally 65 mounted upon said arm, and means associated with said arm to cause swinging of said pivoted gripper whereby the effective distance between said gripping devices may be varied to open and 70 close the bag mouth gripped thereby in order that said spout may be inserted partially into the bag during the filling thereof and that the bag mouth may be drawn closed thereafter.

3. A bag filling machine comprising a filling 75

spout, a pair of bag gripping devices, each comprising means to receive and grip the corner of a bag mouth, located one at each side of said spout, a pivoted arm carrying said gripping devices whereby the bag may be raised and lowered with respect to said spout, one of said gripping devices being rigidly mounted upon said arm and the other of said gripping devices being pivotally mounted upon said arm, means for causing said arm to swing about its pivot, and means associated with said arm to cause said pivoted gripping device to swing toward and away from said fixed gripping device to open and close the bag mouth gripped thereby in order that said spout may be inserted partially into the bag during the filling thereof and that the bag mouth may be drawn closed thereafter.

4. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to cause said arm to pivot about its point of suspension, and a linkage associated with said arm and controlling said pivoted gripping device to cause swinging of said pivoted gripping device as said arm pivots.

5. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to raise said arm thereby bringing the effective gripping points of said gripping devices above the lower edge of said spout in position to receive and grip the edges of the mouth of a bag slipped over said spout; and means to lower said arm to bring the effective gripping points of said gripping devices below the end of said spout in order that a bag may be removed in a lateral direction from said spout.

6. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to raise said arm thereby bringing the effective gripping points of said gripping devices above the lower edge of said spout in position to receive and grip the edges of the mouth of a bag slipped over said spout, means to lower said arm to bring the effective gripping points of said gripping devices below the end of said spout in order that a bag may be removed in a lateral direction from said spout, and means associated with said arm to swing said movable gripping device toward said fixed gripping device in order that the edges of a bag drawn over said spout may be gripped thereby when said arm is raised and to cause said pivoted gripping device to swing away from said fixed gripping device in order that the mouth of the gripped bag may be closed as said arm is lowered.

7. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to raise said arm thereby bringing the effective gripping points of

said gripping devices above the lower edge of said spout in position to receive and grip the edges of the mouth of a bag slipped over said spout, means to lower said arm to bring the effective gripping points of said gripping devices below the end of said spout in order that a bag may be removed in a lateral direction from said spout, and means associated with said arm to swing said movable gripping device toward said fixed gripping device in order that the edges of a bag drawn over said spout may be gripped thereby when said arm is raised and to cause said pivoted gripping device to swing away from said fixed gripping device in order that the mouth of the gripped bag may be closed as said arm is lowered, said means comprising a linkage extending from a fixed point to said pivoted gripping device.

8. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to raise said arm thereby bringing the effective gripping points of said gripping devices above the lower edge of said spout in position to receive and grip the edges of the mouth of a bag slipped over said spout, means to lower said arm to bring the effective gripping points of said gripping devices below the end of said spout in order that a bag may be removed in a lateral direction from said spout, and means associated with said arm to swing said movable gripping device toward said fixed gripping device in order that the edges of a bag drawn over said spout may be gripped thereby when said arm is raised and to cause said pivoted gripping device to swing away from said fixed gripping device in order that the mouth of the gripped bag may be closed as said arm is lowered, said means comprising a linkage extending from a fixed point to said pivoted gripping device, and a resilient attachment of said linkage to said fixed point whereby said linkage will not be forced to move should said gripping device be held against swinging movement even though said arm continues to move.

9. A bag filling machine comprising a filling spout, a pair of bag gripping devices located one at each side of said spout, a pivoted arm carrying said gripping devices, one of said gripping devices being rigidly mounted upon said arm and the other of said gripping devices being pivotally mounted upon said arm, means to raise said arm thereby bringing the effective gripping points of said gripping devices above the lower edge of said spout in position to receive and grip the edges of the mouth of a bag slipped over said spout, means to lower said arm to bring the effective gripping points of said gripping devices below the end of said spout in order that a bag may be removed in a lateral direction from said spout, and means associated with said arm to swing said movable gripping device toward said fixed gripping device in order that the edges of a bag drawn over said spout may be gripped thereby when said arm is raised and to cause said pivoted gripping device to swing away from said fixed gripping device in order that the mouth of the gripped bag may be closed as said arm is lowered, said means comprising a linkage extending from a fixed point to said pivoted gripping device and a resilient attachment of said linkage to said fixed point whereby said linkage

will not be forced to move should said gripping device be held against movement even though said arm continues to move, said means for lowering said arm comprising a cam having a relatively sharp operative portion so as to cause rapid descent of said arm and accordingly rapid closing of the bag mouth immediately after the bag is filled.

10. A bag filling machine comprising a series of filling spouts, a turret upon which said filling spouts are mounted for rotation about a vertical axis, gripping devices arranged in pairs and located one at each side of each of said spouts, an arm carrying each pair of said gripping devices, said arm being pivotally attached to said turret, one of each pair of said gripping devices being rigidly mounted upon its arm and the other of said gripping devices being pivotally mounted upon its arm, means to raise said arm thereby bringing the effective gripping points of said gripping devices above the lower edge of said spout in position to receive and grip the edge of the mouth of a bag slipped over said spout and to lower said arm to bring the effective gripping points of said gripping devices below the end of said spout in order that a bag may be removed in a lateral direction from said spout, and means associated with said arm to swing said movable gripping device toward said fixed gripping device in order that the edges of a bag drawn over said spout may be gripped thereby when said arm is raised and to cause said pivoted gripping device to swing away from said fixed gripping device in order that the mouth of the gripped bag may be closed as said arm is lowered, said means comprising a linkage extending from a fixed point to said pivoted gripping device and a resilient attachment of said linkage to said fixed point whereby said linkage will not be forced to move should said gripping device be held against swinging movement even though said arm continues to move.

11. In the machine of claim 10, said means to raise and lower said arm comprising a fixed cam and a cam follower upon said arm, said cam having a relatively sharp operative portion causing rapid lowering of said arm and closing of the bag mouth immediately after the bag is filled.

12. In the machine of claim 10, said means to raise and lower said arm comprising a fixed cam and a cam follower upon said arm, said cam having a relatively sharp operative portion causing rapid lowering of said arm and closing of the bag mouth immediately after the bag is filled, and a shoe adjacent said cam providing a passageway in which said follower is confined to bring said gripping devices and the mouth of the bag to a predetermined elevation at a predetermined point in the rotation of said turret.

13. In the machine of claim 10, said means to raise and lower said arm comprising a fixed cam and a cam follower upon said arm, said cam having a relatively sharp operative portion causing rapid lowering of said arm and closing of the bag mouth immediately after the bag receives its charge of material, a shoe adjacent said cam providing a passageway in which said follower is confined to bring said gripping devices and the mouth of the bag to a predetermined elevation at a predetermined point in the rotation of said turret, and means to release the bag from said gripping devices at said predetermined point.

14. In the machine of claim 10, said means to raise and lower said arm comprising a fixed cam and a cam follower upon said arm, said cam hav-

ing a relatively sharp operative portion causing rapid lowering of said arm and closing of the bag mouth immediately after the bag is filled, a shoe adjacent said cam providing a passageway in which said follower is confined to bring said gripping devices and the mouth of the bag to a predetermined elevation at a predetermined point in the rotation of said turret, and means to release the bag from said gripping devices at said predetermined point, said cam having a sharp projection adjacent the end of said shoe whereby said arm is immediately raised to again position said gripping devices above the end of said filling spout.

15. In a bag filling machine, a filling spout about which the mouth of a bag may be drawn, gripping devices located one at each side of said filling spout adapted to receive and grip the sides of said bag mouth, said gripping devices being mounted independently of said filling spout and capable of movement relative thereto to lower said bag mouth below the end of said filling spout, and means associated with said gripping devices to increase the distance between the effective gripping points thereof as said bag mouth is lowered and thereby to close the gripped bag mouth, each of said gripping devices comprising gripping jaws and rotatable clamps mounted therein.

16. In a bag filling machine, a filling spout about which the mouth of a bag may be drawn, gripping devices located one at each side of said filling spout adapted to receive and grip the sides of said bag mouth, said gripping devices being mounted independently of said filling spout and capable of movement relative thereto to lower said bag mouth below the end of said filling spout, and means associated with said gripping devices to increase the distance between the effective gripping points thereof as said bag mouth is lowered and thereby to close the gripped bag mouth, each of said gripping devices comprising gripping jaws and rotatable clamps mounted therein, one of said gripping jaws being pivoted to the other of said jaws and comprising a toggle actuating device.

17. In a bag filling machine, a filling spout about which the mouth of a bag may be drawn, gripping devices located one at each side of said filling spout adapted to receive and grip the sides of said bag mouth, said gripping devices being mounted independently of said filling spout and capable of movement relative thereto to lower said bag mouth below the end of said filling spout, means associated with said gripping devices to increase the distance between the effective gripping points thereof as said bag mouth is lowered and thereby to close the gripped bag mouth, each of said gripping devices comprising gripping jaws and rotatable clamps mounted therein, one of said gripping jaws being pivoted to the other of said jaws and comprising a toggle actuating device, the clamp in said pivoted jaw being resiliently urged to project toward said fixed jaw when the jaws are opened in order that the edges of a bag may be temporarily held until said jaws are closed.

18. In a bag filling machine, a rotating turret comprising a filling spout and a pair of gripping devices adapted to receive and grip the edges of the mouth of a bag drawn over said filling spout, said gripping devices comprising toggle actuating means and an operating lever, and a reciprocating shoe beneath which said operating levers are positioned by the rotation of said turret and which

upon reciprocation actuates said toggle actuating means to close said jaws.

19. In a bag filling machine, a rotary turret comprising a filling spout and bag gripping devices adapted to receive and grip the edges of the mouth of a bag positioned on said filling spout, means to lower said gripping devices after the bag is filled in order that the filled bag may be removed in a lateral direction from said filling spout, an arcuate conveyor to support the bottom of the bag as it is filled and lowered thereonto, a bag pushing device mounted upon said turret and positioned between said filling spout and said conveyor to engage the rear edge of said bag as it is filled, and means to advance said pushing device to approach the vertical center line of the bag as its sides are bulged by the inserted material thereby causing its edges to approach each other.
20. In a bag filling machine, a rotary turret comprising a filling spout and bag gripping devices adapted to receive and grip the edges of the mouth of a bag positioned on said filling spout, means to lower said gripping devices after the bag is filled in order that the filled bag may be removed in a lateral direction from said filling spout, an arcuate conveyor to support the bottom of the bag as it is filled and lowered thereonto, and a bag pushing device mounted upon said turret and positioned between said filling spout and said conveyor to engage the rear edge of said bag as it is filled, means to advance said pushing device to approach the vertical center line of the bag as its sides are bulged by the inserted material thereby causing its edges to approach each other, means to remove the filled bag from said turret comprising a tangentially directed conveyor adapted to grip and convey the filled bag as it is deposited therein by said turret, and means to retract said bag pushing device from its advanced position as the bag is released from said turret.
21. In a rotary bag filling machine, a bag pushing device comprising an arm pivoted to the machine and rotating therewith, a cam follower mounted upon said arm, and a fixed cam with which said follower engages adapted to advance and retract said pushing device arcuately with respect to the axis of rotation of said filling machine.
22. In a rotary bag filling machine, a bag pushing device comprising an arm pivoted to the machine and rotating therewith, a cam follower mounted upon said arm, and a fixed cam with which said follower engages adapted to advance and retract said pushing device arcuately with respect to the axis of rotation of said filling machine, said pushing device being advanced to follow the inwardly drawn edge of the bag as its sides are outwardly bulged by the charge of material and being retracted as the filled bag is removed from the machine.
23. In the combination of a rotary turret type filling machine in which a bag is filled with a charge of material during the rotation thereof, and a tangentially situated conveyor within which the filled bags are received and removed from said rotary machine; means in said machine to close the mouths of the bags and bring them to a predetermined elevation during the rotation thereof, and means in said conveyor to receive the closed mouths of the filled bags and maintain them in direct alignment in said conveyor comprising a pair of gripping chains, feed wheels about which said chains are positioned, the axes of said wheels being substantially upon a line normal to said conveyor through the axis of said machine, the peripheries of said wheels being separated to provide a gap between said gripping chains, and means whereby said gripping chains are brought resiliently into gripping contact at substantially one-third of a bag length from the axes of said feed wheels.
24. In the combination of a rotary turret type filling machine in which bags are filled with a charge of material during the rotation thereof, and a tangentially situated conveyor within which the filled bags are received and removed from said rotary machine; means in said machine to close the mouths of the bags and bring them to a predetermined elevation during the rotation thereof, and means in said conveyor to receive the closed mouths of the filled bags and maintain them in direct alignment in said conveyor comprising a pair of gripping chains, feed wheels about which said chains are positioned, the axes of said wheels being substantially upon a line normal to said conveyor through the axis of said machine, the peripheries of said wheels being separated to provide a gap between said gripping chains, means whereby said gripping chains are brought resiliently into gripping contact at substantially one-third of a bag length from the axes of said feed wheels, and means whereby the filled bags are released from the machine at substantially the point in its rotation coinciding with the meeting point of said gripping chains.
25. In a rotary bag filling machine, a bag pushing device comprising an arm pivoted to the machine and rotating therewith, and means to advance and retract said pusher arcuately from and toward a normal position rearwardly of a bag supported by said machine and being filled.
26. In a rotary bag filling machine, a bag gripping device mounted upon the machine and rotating therewith having an operating lever, and reciprocating means at the side of the machine in position to have said lever pass closely thereby, and means to reciprocate said first named means in timed relation to the rotation of the machine whereby to actuate said operating lever as said gripping device is rotated thereby.

HOWLAND F. BRIGGS.
